US0D1039400S

(12) **United States Design Patent** (10) **Patent No.:** **US D1,039,400 S**
(45) **Date of Patent:** **** Aug. 20, 2024**

(54) **TRAFFIC MEASURING DEVICE**

(71) Applicant: **JENOPTIK UK Ltd**, Camberley (GB)

(72) Inventor: **Kirsch Michael**, Camberley (GB)

(73) Assignee: **Jenoptik UK Ltd.**, Camberley (GB)

(**) Term: **15 Years**

(21) Appl. No.: **35/514,726**

(22) Filed: **Mar. 23, 2022**

(80) **Hague Agreement Data**

Int. Filing Date: **Mar. 23, 2022**

Int. Reg. No.: **DM/221996**

Int. Reg. Date: **Mar. 23, 2022**

Int. Reg. Pub. Date: **Jul. 15, 2022**

(51) **LOC (14) Cl.** **10-04**

(52) **U.S. Cl.**

USPC **D10/70**

(58) **Field of Classification Search**

USPC D10/60, 65, 70, 75, 78, 80, 103, 106.5;
D24/187; D14/230

CPC G08G 1/0133; G08G 1/04; G08G 1/0141;
G08G 1/08
